UNITED STATES PATENT OFFICE.

WILLIAM C. MAYO AND JOHN HOULEHAN, OF EL PASO, TEXAS, ASSIGNEES
OF ONE-THIRD TO GEORGE E. BRIGGS, OF EL PASO, TEXAS.

STARTER FOR ELECTRIC MOTORS.

No. 856,540.

Specification of Letters Patent.

Patented June 11, 1907.

Application filed February 11, 1907. Serial No. 356,821.

To all whom it may concern:

Be it known that we, WILLIAM C. MAYO and JOHN HOULEHAN, citizens of the United States, residing at El Paso, in the county of 5 El Paso and State of Texas, have invented a new and useful Starter for Electric Motors, of which the following is a specification.

This invention has reference to improvements in starters for electric motors and is 10 designed more particularly for starting direct current shunt wound motors, and its object is to provide a starter which, when the switch is thrown, will automatically and gradually cut out the starting rheostat by 15 and in accordance with variations in line current due to the speeding up of the motor.

To this end, the invention consists essentially in means for putting the rheostat switch arm under stress tending to move it in 20 a direction to cut out the resistances and providing a release mechanism which will control the speed of movement of the rheostat arm by and in accordance with the fluctuations of current set up in the circuit by the 25 increasing speed of the motor. Since the rheostat is cut out step-by-step, there will be a surge of current with each step and with each increase in the speed of the motor. This 30 surge of current acting on an electro-magnetic device will release the rheostat arm to move under the stress of a spring, and as soon as the equilibrium has again been established between the field and armature 35 circuits the release mechanism will again catch the rheostat arm. The arrangement is such that the current surge will permit a movement of the rheostat switch arm across the contacts coincident with the surges and to an extent commensurate therewith.

40 The invention will be clearly understood from the following detailed description taken in connection with the accompanying drawings forming part of this specification, in which,

45 Figure 1 is a partially diagrammatic view of the improved motor starter in the initial position; Fig. 2 is a similar view of the motor starter in the first position when the rheostat arm is about to move across the rheostat contacts; and Fig. 3 is a side view, partially in section, of the switch mechanism.

50 Referring to the drawings, there is shown the usual base plate or panel 1, which may be of slate or other insulating material com-

monly used for the purpose. Passing through this plate near the bottom is a stud 2 having an annular flange 3 for engaging against the base plate 1 and by means of which, together with a nut 4 screwed on to the stud where it extends through the back of the base plate, 55 the said stud is securely fastened to said base plate, and this nut 4 may confine the terminal of a conductor 5, thus putting said conductor into good electrical connection with the stud. Near the other end of the 60 base plate or panel there is arranged a series of contact studs 6 having stems, not shown, passing through the base plate and receiving nuts 7 which confine the studs 6 to the base plate and also clamp the terminals of 65 the leads 8 coming from the rheostat coils 9, diagrammatically represented in Figs. 1 and 2 but which will be constructed and located in the usual manner back of the panel or base plate 1. The rheostat coils are arranged as 70 usual in series, and from intermediate points the leads 8 branch off to the contacts 6. One end of the rheostat is connected by a branch conductor 10 to a binding post 11 on the base plate, which binding post 11 is, in turn, connected 75 by a conductor 12 to one brush 13 of the armature 14 of an ordinary shunt wound motor, the other brush 15 of said armature being connected by a branch conductor 16 to a conductor 17 coming from a terminal 18 of the power circuit, in which circuit will, of course, be included the usual main switch, 80 not shown. The other terminal 19 of the power circuit is connected by a conductor 20 to a binding post 21 which, in turn, connects 85 by conductor 22 to a contact stud 23 adjacent to the stud 6 connected to the end of the rheostat, which is coupled by the conductor 10 to the binding post 11. From the conductor 17 coming from the terminal 18 is 90 branched the field 24 of the shunt wound motor, which field, as well as the armature 14 of the motor, is only diagrammatically represented in the drawings, and this diagrammatic representation is to be understood as 95 indicative of any approved or suitable type of shunt wound motor. The other terminal of the field is connected by a conductor 25 to a binding post 26 on the base plate, and this binding post 26 is connected by conductor 27 to a magnet coil 28, to be hereinafter referred to, and this magnet coil is connected by a 100 conductor 29 to the end of the rheostat coils 105

9 remote from the end connected by the conductor 10 to the binding post 11.

Leaving the circuit connections for the time being, we will now describe the switch arm mechanism and afterward trace out the circuits and the operation of the switching devices.

Upon the stud 2 is mounted the hub 30 of a lever 31 which may be termed a retaining lever. This hub 30 is cored out at the outer end and there receives a spring 32 and a retaining nut 33 screwed on to the end of the stud, the said nut being provided with an annular groove 34 to receive the end of the cored out portion of the hub 30. The hub 30 extends to a point adjacent to the flange 3 on the stud and is stepped or reduced in diameter to receive certain parts to be hereinafter referred to. One of these parts is the hub 35 of a switch arm lever 36, the outer or free end of which is movable across and makes contact with the contact studs 6 before referred to, the said studs being arranged on an arc of which the axis of the stud 2 is the center. It will be seen that the hub of the retaining lever 31 has a journal bearing upon the stud 2, and the spring 32 is so connected to the stud 2 and hub 30 that it will tend to maintain the retaining lever 31 in the position shown in Fig. 1 and will be put under stress when the retaining lever 31 is moved to the position shown in Fig. 2, where it will be maintained by the attraction of the pole pieces 37 of the magnet 28, which pole pieces will then engage an armature block 38 fast on the lever 31; this magnet constituting an electromagnetic retaining device such as is used in motor-starting switches. The hub 35 of the switch arm 36 is also cored out and receives a spring 39 fast at one end to the said hub 35 and at the other end to the hub 30 of the retaining lever 31, this spring being put under stress when the retaining lever 31 is moved to the position shown in Fig. 2 and tending to carry the switch arm 36 from the position shown in Fig. 2 over the series of contact studs 6 until it is in position to bridge the contact studs 6 and 23 after the rheostat coils have all been cut out of circuit.

Loosely journaled upon the hub 30 on one of the step portions thereof and adjacent to the hub 35 is a ratchet wheel 40, and carried by the switch arm 36 is a block 41 having a stem 42 extending through brackets 43 projecting from said switch arm 36, and this block 41 is provided with ratchet teeth 44 movable into and out of the path of the teeth of the ratchet wheel 40. This block 41 is constrained to move to a position to bring its teeth 44 into engagement with the ratchet wheel 40 by a spring 45 surrounding the stem 42 between the brackets 43 and in contact with one of the brackets and a collar 46 on said stem. The upper end of the stem

42 is beveled, as shown at 47, and this beveled end, when the block 41 is moved against the stress of the spring 45, is arranged to be engaged by the toothed end 48 of a spring arm 49 carried by a post 50 fast on and projecting from the base plate or panel 1, and a stop pin 51 limits the movement of the arm 49. Projecting from the block 41 is a pin 52 which is located in the path of a cam face 53 formed on a boss 54 integral with or secured to the rear face of the retaining lever 31. The cam face 53 terminates in a hook 55 which, after the cam face 53 has engaged with the pin 52 and raised the latter against the stress of the spring 45 out of engagement with the ratchet wheel 40, will engage said pin 52 for a purpose which will hereinafter appear.

Upon one side of the hub 35 of the switch arm 36 is formed a cam projection 56 in the path of the free end of a lever 57 pivoted to a stud 58 rising from the base plate 1. This lever 57 carries a bearing roller 59 on its free end to engage the face of the cam 56 and this lever is provided with a series of perforations 60 to receive the end of a spring 61, the other end of which engages an arm 62 pivoted on a stud 63 rising from the base plate 1 adjacent to the ratchet wheel 40. Carried by the arm 62 at a point coincident with its axis upon the pivot pin 63 is an anchor escapement 64 in the path of the teeth of the ratchet wheel 40, and the other or free end of the arm 62 carries an armature 65 in operative relation with the solenoid 66, one terminal of which is connected by the conductor 5 to the stud 2 and the other terminal of which is connected by a conductor 67 with the binding post 21 before referred to. The retaining lever 31 is provided at its outer end with a manipulating handle 68 which may be of insulating material and is arranged to make contact with a contact stud 69 rising from the base plate 1 adjacent to the contact stud 23 and magnet 28, and this stud 69 is connected by a conductor 70 to the conductor 29 before referred to.

Let it now be assumed that the retaining lever 31 is in the "off" position, that is, in the position shown in Fig. 1, overlying the switch arm 36. The service switch is closed but as yet no current will flow to the motor. The operator now takes hold of the knob or handle 68 and moves the retaining lever 31 to the right, as viewed in Fig. 1, to the position shown in Fig. 2, that is, until the armature 38 is in contact with the poles 37 of the magnet 28 and the retaining lever 31 has made contact with the contact stud 69, which latter is in communication by way of the conductor 70 with the conductor 29. A circuit is now complete by way of the terminal 18 from the power circuit through conductor 17, the motor field 24, conductor 25 to the binding post 26, thence by conductor 130

27 through the magnet 28, energizing the latter and locking the retaining lever 31 in the position shown in Fig. 2. From the magnet spool 28 the current will pass by conductor 29 to branch conductor 70, thence to the retaining lever 31, to the stud 2, thence by way of conductor 5 to the solenoid spool 66, thence by conductor 67 to the binding post 21, and by conductor 20 to the other terminal 19 of the power circuit. When the retaining lever 31 was moved to the right as viewed in Figs. 1 and 2, the springs 32 and 39 were put under tension. When the retaining lever 31 overlaid the switch lever 36 prior to the movement just described, the cam face 53 had raised the block 41 by engagement with the pin 52 until the end 47 of the stem 42 had been engaged by the catch end 48 of the arm 49. However, when the lever 31 had been moved, as just described, to the right in Figs. 1 and 2, the cam face 53 was removed from engagement with the pin 51 and the teeth 44 on the block 41 were moved by the spring 45 into engagement with the teeth of the ratchet wheel 40, thus releasing the end 47 of the stem 42 from engagement with the hooked end 48 of the arm 49. In this position of the parts the switch arm 36 is locked to the ratchet wheel 40 and at the same time the ratchet wheel 40 is locked from movement by the engagement therewith of one of the teeth of the anchor escapement 64 before mentioned, and in this position of the parts the roller 59 of the lever 57 rests upon the highest point of the cam 56 carried by the hub 35 of the switch arm 36, so that the arm 62 carrying the solenoid armature or core 65 is held in a position to carry the solenoid core 65 from out the said solenoid by the stress of the spring 61 with a force due in part to the upward position of the lever 57 when engaged by the highest part of the cam 56. It will also be evident that when the retaining lever 31 was moved to the position shown in Fig. 2 the current coming in at 18 divides at the junction of the conductor 16 with the conductor 17 and the greater portion flows through the brush 15, armature 14, the brush 13, the conductor 12, binding post 11, conductor 10, all of the resistance coils 9 in series, thence by conductor 29 and uniting at the conductor 70 with the current that has passed through the field. The relative resistance of the retaining magnet coil 28 and the resistance coils 9 is so adjusted that the major portion of the current will pass through the armature, and the field under these conditions will be but weakly energized.

60 In considering the further operation of the starting device, it will be assumed that the starting current flowing through the armature when the rheostat is all included in the circuit may be fifty per cent. over full-load current, and this current will, of course, flow

through the solenoid 66, which latter, however, is adjusted to overcome the spring 61 with a current but little in excess of the full-load current. The result is that the core 65 will be pulled down into the solenoid against the action of the spring 61 and the upper tooth of the anchor escapement will be pulled out from engagement with the teeth of the ratchet wheel 40 while the lower tooth will be moved into engagement therewith, the parts being so adjusted that a slight forward movement of the ratchet wheel has been permitted, after the manner of an ordinary anchor escapement. The motor having received current, it will start and begin to rotate and will develop a certain counter electromotive force which will oppose the line current until only sufficient current will flow through the motor to maintain its load at the speed already attained. This will weaken the pull of the solenoid and the spring will lift the core 65 against the pull of the solenoid which will rock the anchor escapement 64 so that its upper tooth is again in the path of the teeth of the ratchet wheel 40 and the latter has been permitted to turn a distance of one tooth, thus bringing the arm 36 into engagement with the first active contact stud 6 to cut out the first of the series of resistance coils 9. This movement of the switch lever 36 is caused by the tension of the spring 39, as before explained. The speed of the motor has in the meantime not increased, and, consequently, there is a surge of current due to the cutting out of the first of the series of resistance coils 9, hence the solenoid is again strengthened and the anchor escapement 64 is rocked on its pivot against the action of the spring 61 and, on the increased counter electromotive force developed by the increased speed of the motor, the solenoid is again weakened as before and the ratchet wheel 40 is released to move a distance of one tooth and the switch arm 36 moves to the second contact. This action is repeated again and again until the switch arm 36 has reached the last of the contact studs 6 in its path where all the resistance coils are cut out and the switch arm bridges the last contact 6 and the contact stud 23 in direct communication through the conductor 22, binding post 21 and conductor 20 with the terminal 19 of the power circuit, at which time the motor is supposed to be running at full speed under full load.

As the motor approaches full speed the current taken from the power circuit correspondingly decreases from the fifty per cent. overload to normal load and the pull of the solenoid 66 is, therefore, progressively lessened as the motor speeds up. For this reason the pull of the spring 61 is correspondingly lessened automatically by the action of the cam 56 upon the lever 57 since this is so arranged as to move with the switch arm 36

and allow the free end of the lever 57 to progressively approach the arm 62 and thereby lessen the pull of the spring 61 so as to compensate for the lessened pull of the solenoid 66.

- 5 When the switch lever 36 makes contact with the stud 23 and the contact stud 6 adjacent thereto it will be observed that the solenoid 66 is shunted by the two arms 31—36 and the current flowing from binding post 26 through the magnet 28 and by way of conductor 70 to the contact stud 69 will flow by way of the retaining lever arm 31 to the switch arm 36, thence by contact stud 23, conductor 22, binding post 21 and conductor 20 to the terminal 19 of the power circuit, and the armature circuit coming by conductor 12 to the binding post 11 is completed through the conductor 10 to contact 6, thence through the switch arm 36 to the contact 23, and from thence, as before, to the power circuit terminal 19.

It will be seen that the operation of the starting devices is entirely automatic and that the movement of the switch arm 36 to 25 cut out the resistances is strictly in accordance with the increasing speed of the motor; thus all danger to the motor from a heavy starting current, such as might occur from a too rapid movement of the switch arm to cut 30 out the resistances when operated manually by a careless operator is entirely avoided.

Now, let it be assumed that it is desired to stop the motor. The main switch is open. Immediately the magnet 28 is deenergized and the spring 32, acting upon the retaining 35 lever 31 will carry the same toward the left in Fig. 2, and, finally, to the position shown in Fig. 1. As the retaining lever 31 moves toward the left the cam face 53 will engage the 40 pin 52 on the block 41 and lift the teeth 44 out of engagement with the teeth of the ratchet wheel 40, and the hook end 55 will ultimately engage the pin 52 and those parts constituting the connection between the 45 lever arm 31 and the switch arm 36 will cause the said lever 31 to carry the switch arm 36 to the left, as viewed in Figs. 1 and 2, until a stop-pin 71 is engaged by said arms and their further movement to the left thereby stopped. 50 At this point the beveled end 47 of the stem 42 of the block 41 is engaged under the hooked end 48 of the arm 49 and the switch arm 36 is thereby prevented from movement toward the right when, as has been heretofore explained, the lever 31 is moved to the right to again set the motor in operation. When the switch arm 36 is in the extreme 55 left or "off" position its outer end may conveniently make contact with an idle contact 60 stud 72, indicated by dotted lines.

The magnetic circuit of the solenoid 66 is preferably a double one with practically one air gap, the other being very slight. The solenoid may be ironclad with two poles and 65 the armature or core may be a plunger work.

ing through an iron head. This renders the solenoid secure against mechanical injury and produces a very efficient structure. The iron in the magnetic circuit should be liberal so as to have very low magnetic density, thus securing sensitiveness to the small current changes since, if it worked too near the saturation point, it might not respond properly should the spring get a little out of adjustment. While the lack of sensitiveness would be most apparent when the motor was nearly up to normal speed, it is well to provide against such a contingency and if such a solenoid as just described is used the lack of sensitiveness will not occur.

Of course the field current always passes through the solenoid while the latter is in operation, but as this current is a constant factor, it has no bearing on the operation of the solenoid which need only be properly designed to take care of it.

When the switch arm 36 has reached the contact 23 the teeth of the block or dog 41 will be lifted out of engagement with the ratchet wheel 40 by the cam face 53.

We claim:

1. In a motor starter, a propelling means for the starting switch having a constant tendency to move it across the steps of the starting resistance in succession, and means controlled by the variation of current strength due to the cutting out of the successive groups of resistances of the starter for controlling the movement of the starting switch across the terminals of the resistances.

2. In a motor starter, a propelling means for the starting switch having a constant tendency to move it across the steps of the starting resistance in succession, a detent controlling the movement of the switch arm, and an electro-magnetic controlling device for the detent sensitive to variations in the starting current to permit a movement of the switch arm in accordance with said variations of the starting current.

3. In a motor starter, a series of resistance coils, a switch arm engaging the terminals of said coils, another arm connected to the switch arm by a spring connection, means for holding said arm in a position to put the spring connection under stress, an escapement for controlling the movement of the switch arm, and an electro-magnetic control for said escapement sensitive to variations in the starting current.

4. In a motor starter, a series of resistance coils, a switch arm arranged to engage the terminals of said coils, another arm having a spring connection with the switch arm and movable to put the spring connection under stress, a ratchet wheel mounted upon the axis of the switch arm, a toothed lock or pawl connecting said switch arm to said ratchet wheel, a detent for said ratchet wheel, and an electro-magnetic actuating device for said

detent sensitive to variations in the starting current.

5. In a motor starter a series of resistances, a switch arm arranged to make contact in succession with the terminals of said resistances, another arm, a spring connection between the two arms put under stress by the movement of the said other arm, a ratchet wheel having its axis of rotation coincident with the axis of the switch arm, a spring-actuated pawl movable into and out of engagement with the ratchet wheel, a fixed detent for engaging the pawl when out of engagement with the ratchet wheel and for then holding the switch arm from movement under the stress of the spring, an escapement for the ratchet wheel, and an electro-magnetic controlling device for the escapement sensitive to variations in the starting current.

6. In a motor starter, a series of resistances, a switch arm movable over the terminals of said resistances in succession, another arm, a spring connection therefrom to the switch arm, a ratchet wheel mounted on the axis of the switch arm, a pawl on the switch arm engaging the ratchet wheel, a spring-retained detent for the ratchet wheel, an electro-magnetic controlling mechanism for the detent sensitive to variations in the starting current, and means for varying the tension of the spring connected with the detent in direct ratio to the power of the detent operating mechanism.

35 7. In a motor starter, a series of resistances, a switch arm movable in succession over the resistance terminals, another arm, a spring connection therefrom to the switch arm, a ratchet wheel mounted to turn upon the same axis as the switch arm, a spring-actuated pawl connection between the switch-arm and the ratchet wheel, a cam upon the other arm engaging said spring-actuated pawl to move it out of engagement with the ratchet wheel, a detent for the ratchet wheel, and electro-magnetic controlling means for the detent sensitive to variations in the starting current.

8. In a motor starter, a series of resistances, a switch arm movable over the resistance terminals in succession, a ratchet wheel mounted to turn upon the same axis as the switch arm, a spring-actuated toothed pawl on the switch arm for engaging the teeth of the ratchet wheel, a fixed detent in the path of said pawl for holding the latter out of engagement with the ratchet wheel and at the same time holding the switch arm against movement, another arm mounted upon the same axis as the switch arm, a cam upon said

arm for operating said pawl, a detent for said ratchet wheel, electro-magnetic means sensitive to variations in the starting current for controlling said detent, a spring acting on said detent in opposition to the electro-magnetic controlling means, a lever carrying said spring, and a cam movable with said switch arm and controlling said lever to vary the pull of the spring attached to the detent.

65 9. In a motor starter for shunt wound motors, a series of resistances included in the armature circuit of the motor, a switch arm for successively cutting out said resistances, electro-magnetic means sensitive to variations in the starting current for controlling the movement of the switch arm step by step and included in the motor circuit when the resistances are included therein, and means for shunting said electro-magnetic controlling devices when the resistances are cut out 70 of the motor circuit.

10. In a motor starter, a series of resistances, a switch arm arranged for successive engagement with the terminals of said resistances, another arm, springs put under tension thereby, one of said springs connecting the two arms, an electro-magnetic retaining device for the last-named arm included in the motor circuit, electro-magnetically controlled means sensitive to variations in the power circuit for permitting the switch arm to move under the stress of the spring, a coupling mechanism connecting the switch arm to the said electro-magnetically controlled means, and means carried by the 85 other arm for uncoupling the said switch arm and returning it to the initial position.

11. In a motor starter, a series of resistance coils, a spring-actuated switch-arm movable across the terminals of the resistance coils in succession under the action of the spring, a detent for controlling the movement of the switch-arm, and an electro-magnetic controlling device for the detent sensitive to variations in the starting current to 90 permit the movement of the switch-arm under the impulse of its spring in accordance with said variations of the starting current.

In testimony that we claim the foregoing as our own, we have hereto affixed our signatures in the presence of two witnesses.
